JAY M. JOHNSON AND CHARLES SULFER, OF CHICAGO, ILLINOIS,
ASSIGNORS TO COIN COUNTING MACHINE COMPANY, A CORPO-
RATION OF NEW YORK.

COIN-COUNTING MACHINE.

No. 824,794.

Specification of Letters Patent.

Patented July 3, 1906.

Application filed May 23, 1903. Serial No. 158,441.

To all whom it may concern:

Be it known that we, JAY M. JOHNSON and CHARLES SULFER, citizens of the United States, and residents of Chicago, Cook county, Illinois, have invented certain new and useful Improvements in Coin-Counting Machines; and we do hereby declare that the following is a full, clear, and exact description of the same, reference being had to the accompanying drawings, and to the letters of reference marked thereon, which form a part of this specification.

This invention relates to an improvement in coin-counting machines, and is shown embodied in relation with a machine similar to that set forth in the application for United States patent to Jay M. Johnson, filed on the 22d day of September, 1902, Serial No. 124,284, though obviously the same may be employed in conjunction with many different kinds of counting devices.

Heretofore mechanical counting devices have been used for many different purposes, and the device set forth in the application above referred to counts coin in bulk with great rapidity and absolute accuracy. A device, however, has never before been constructed whereby in conjunction with any automatic coin-counting machine an automatically-operating locking-register is actuated thereby to accurately count a predetermined number of coins into a package. Inasmuch as coin is usually put up in rolls for convenience in counting and transportation the importance of this is evident.

The object of this invention is to provide a simple, durable, and absolutely-accurate device adapted to be attached to any coin-counting machine and to operate automatically to deliver a predetermined number of coins into a conveniently-located package for the purpose of forming into rolls or the like.

The invention consists in the matters hereinafter described, and more fully pointed out and defined in the appended claims.

In the drawings, Figure 1 is a fragmentary top plan view of a counting-machine provided to a device embodying our invention. Fig. 2 is a section taken on line 2 2 of Fig. 1. Fig. 3 is a rear elevation of the registering mechanism, showing the counting-machine broken away and the coin-tube and the coin-package in vertical section. Fig. 4 is a verti-

cal section of one of the detents of the locking gear-wheel. Fig. 5 is an enlarged vertical section taken centrally through the locking gear-wheel of the registering mechanism, showing the pivot-bolt partly in elevation. Fig. 6 is a section taken on line 6 6 of Fig. 3. Fig. 7 is a vertical section of one of the coin-packages, showing the same filled with coin shown in elevation. Fig. 8 is a fragmentary detail similar to Fig. 1, but showing the parts adjusted to count continuously in bulk.

As shown in said drawings, our invention, for convenience of illustration, is embodied with a coin-counting machine, such as set forth in the aforesaid application for patent. Said machine embraces, among other details, a substantially circular base-plate A, having a shaft d' journaled centrally therein, on which is secured a coin-carrying disk A', provided with a plurality of teeth or projecting arms a, which successively engage the coin and sweep them past a registering-disk B, whereby the counting mechanism and registering mechanism is actuated. Said registering-disk is also provided with teeth which successively contact with the coin as the same are carried past by the teeth a. Said coin-carrying disk is actuated, as shown, by means of a crank D, secured on a shaft d, extending radially beneath the base-plate A, and provided with a beveled pinion d' at its inner end, which meshes with the beveled gear D' of the shaft d', on which the coin-disk is secured. As shown, said crank D is secured on the shaft d by means of a spring-clutch comprising conveniently a pin d'', extending transversely through the ends of the shaft and adapted to engage in a complementary transverse groove on the outer side of the hub of the crank and against which the crank is normally held by means of a spring d'.

The registering means, as shown, are supported upon a laterally-projecting base-plate E integral with the base-plate A. Said plate E is provided near its periphery with a slightly-raised flange e, on which is secured the covering-plate E', which fits closely above the registering-disk B and through which the shaft b extends. A beveled pinion b' is rigidly secured on said shaft above the cover-plate and meshing with a like beveled pinion f of the register F, which may be of any preferred type and is adjusted to indicate correctly the

number of impulses or movements of the registering-disk. Rigidly secured upon the covering-plate E' is the bench G, provided with an upwardly-extending boss g, through which 5 the upper end of the shaft b passes, having on its upper end the pinion b³. A boss g' similar to that already described is provided at one end of said bench, on which is journaled a locking-gear-wheel H, having a number 10 of teeth thereon bearing a direct ratio to the number of coins it is desired to count to the package and which meshes with said pinion b³. As shown, said locking-wheel H is secured on said boss g' by means of a set-screw h, beneath the head of which is secured a resilient washer h', which acts to regulate the tension on said locking-wheel and to insure accuracy of movement. Secured on 15 said locking-wheel are one or more rotatable stops h², each provided with an integrally-projecting arm h³, which extends along the upper surface of the locking-wheel and the end of which extends to near the periphery thereof and when so positioned is adapted to 20 engage against a stop-pin h⁴, which acts to hold the arm from rearward movement. Pivotal secured either on said bench G or on a portion of the frame of the coin-counter, as preferred, is the pivoted locking bar or lever 25 I, one end of which normally projects over the periphery of the locking-gear H in position to be engaged by the arm h³ of said detent and the other end of which projects beyond the pivot and is afforded a positive support 30 on a standard g² integral with said bench. On its inner side adjacent to the pivot said locking-bar is provided with an inwardly-directed arm or projection i, from the extremity of which the edge of the lever curves rearwardly to the inner extremity of said bar, as 35 shown in Fig. 1, affording a curved cam-surface, so that should the rear end thereof be swung outwardly from the periphery of the locking-gear the projecting arm h³ of the detent h², moving along the curved inner side of 40 said lever and engaging the projection i, acts to swing the end of said lever back over the periphery of the gear in position to abut the arm h³ when it next arrives in the position 45 shown in Fig. 1, thus affording a positive stop for the device, causing the clutch to release, and preventing further operation until the machinery is adjusted. Should, however, the arm h³ of the detent or detents be turned 50 inwardly, so as to miss said arm i, the locking-bar will of course not be shifted, and as a consequence the machine will operate continuously. Beneath the coin-exit aperture in the bed-plate A of the machine is the delivery 55 pipe or spout J, having hooks j thereon, which permit a canvas sack or the like to be engaged thereon if the coin-counter is to be used for ordinary counting purposes or for counting large quantities of coin in bulk. At the 60 lower end of said delivery-pipe is provided a

cylindric portion wherein to secure the package-supporting means to receive the coins when counted in rolls. Preferably for this purpose a removable coin-tube is used. Said supporting device comprises a collar K, adapted to fit closely to said cylindric portion of said delivery-pipe and provided with a set-screw k to removably secure the same thereon. Rigidly secured to said collar in position to register with the coin-delivery pipe 70 is the tube K' of a length slightly greater than the length of the package in which the coin are to be received and having the lower end thereof cut obliquely, as shown in Fig. 3, to permit the coin-package to be quickly 75 inserted thereon. Pivotal supported to swing on one side of said collar K is the depending resilient bracket-arm k², comprising a plate of steel or other suitable metal bent near its lower end to provide a horizontally- 80 projecting support for the bottom of the coin-package and a depending end portion k³ to permit of ready manual engagement. The packages (indicated by K²) are shown rectangular in cross-section, though obviously various shapes might be used, if desired. 85

The operation is as follows: The machine constructed as described and provided with such a register and clutch-crank mechanism, the coins may be dumped into the top of the 90 machine or otherwise fed to the coin-carrying disk, and as the same are successively swept by the registering-disk B the shaft b is revolved, actuating the register. Should the projecting arms h³ of the detents be all turned 95 inwardly, the ends of the locking-bar I adjacent to the locking-gear may be swung outwardly from the periphery and the machine may be used as long as desired to count coin in bulk in the usual manner. Should it at 100 any time, however, be desired to count the coin into packages, each containing a number corresponding to a limited extent with the denomination of the coin, coins of various denominations are placed in rolls of 105 fifty, one hundred, or twenty. For this purpose the gear-wheel H is provided with a number of teeth having a direct ratio to the number of coins to be counted into the packages, and the detents are arranged near the 110 periphery to stop and lock the mechanism when exactly that number of coins have been 115 counted. This is readily accomplished by making the number of teeth on the locking gear-wheel H an exact multiple of the number of teeth on the pinion b³. When the machine is empty, the locking-wheel is turned until one of the projecting arms h³ engages 120 against the end of the locking-bar I, and the end of the stop-lever is then swung outwardly 125 beyond the periphery of the gear. The machine is now set for use, and the coin-package K² is slipped over the coin-tube and supported upon the bracket-arm k², as shown in Fig. 3. When the crank is turned, the coins are 130

passed into the coin-tube by the coin-disk, each successively actuating the registering-disk and shaft *b* and each turning the gear *H* proportionately, the projecting arm *h*³ on the 5 detent soon engaging the inward projection *i* of the locking-bar and swinging said lever end inwardly over the periphery of the locking-wheel in position to be engaged by the arm *h*³ of the detent next approaching the 10 same. This of course acts to immediately block the further movement of the locking-wheel and registering-shaft *b* and creates sufficient resistance to permit the clutch on the handle or crank *D* to slip, thereby immediately locking the machine from further operation. 15

Obviously the construction is capable of many variations and may be employed in connection with any counting-machine, either 20 for coin or other articles, as preferred, and many details of construction may be varied without departing from the principles of this invention.

We claim as our invention—

25 1. The combination in a coin-counting machine of a coin-actuated wheel, a registering device adapted for adjustment to count and register a predetermined number, a locking-wheel and a swinging arm adapted to engage therewith and lock the machine when the number has been registered.

30 2. The combination in a counting-machine, of a register actuated by the articles counted, a locking-wheel, a pivoted detent thereon and a pivoted lever adapted to engage said detent and lock the machine from further operation.

35 3. The combination in a coin-counting machine, of means operated by successive coins acting to register the number of coins counted, a horizontal locking-wheel, a pivoted lever adjacent said wheel, means on said wheel adapted to engage said lever and lock the machine from movement, there being an inwardly-directed projection on said lever adapted to contact with said means and normally throw the lever to locking position.

40 4. The combination in a coin-counting machine, of a registering device carried thereon, a locking-wheel, a lever pivoted adjacent said wheel, a pivoted detent on said wheel adapted when in one position to permit the machine to count in bulk and when in another position, to lock the machine at a predetermined count, said detent being adapted to engage a part on said lever and swing it to locking position.

45 5. In a coin-counter the combination with actuating mechanism, of an automatic register adapted to accurately register the passage of the coin therethrough and adjustable means adapted when set in one position to lock the machine at a predetermined count and when set in an opposite position, to permit the machine to count in bulk.

6. In a coin-counting machine, the combination with a coin-register secured thereon and operated by the passage of coins, of a locking-wheel, a lever pivoted adjacent said wheel, adjustable means on said wheel adapted when in one position, to contact with said lever and stop the machine there being an inwardly-directed projection on said lever adapted to engage said means and swing the lever inwardly when the same is again set in motion. 75

7. In a device of the class described, the combination in a coin-counter, of automatic registering means thereon, a stop-lever and a pivoted detent adapted to be thrown into and out of engagement with the lever to permit the passage of coins through the machine continuously or in lots, each lot containing a predetermined number and lock the machine automatically when the machine registers 85 the passage of said number therethrough.

8. In a device of the class described the combination with a coin-counter, of automatic registering means thereon, a stop-lever adapted to be adjusted to permit the passage 90 of coins through the machine continuously or in lots, each lot containing a predetermined number, and to lock the machine automatically when the machine registers the passage of said number therethrough, a coin-spout and a bracket dependent therefrom and adapted to support a package of a size appropriate for the number of coins counted. 95

9. The combination with a counting-machine, of a chute, a removable delivery-pipe secured thereon and adapted to fit within a wrapper or package, a swinging bracket adapted to support said package and automatic means operated by the passage of the coin in the machine adapted to deliver into 105 the package a predetermined number of coins and to lock the machine from further operation when the coins are so delivered.

10. The combination with a rotative shaft, of actuating means thereon having yielding spring-pressed engagement with the shaft mechanism operated from said shaft and adapted to move coins singly to a point of discharge, a coin-disk positioned to be actuated successively by the coins, a register operated by the coin-disk and a stop mechanism adapted for adjustment to limit the number of rotations of the coin-disk. 110 115

11. The combination with a coin-counting mechanism, of an actuating-crank therefor having spring-pressed engagement with its shaft, a register operated by the passage of coins through the machine, a revoluble plate movable simultaneously with the registering means, pivoted projections thereon and a locking-lever adapted to be swung into position to engage one of said projections and to lock said plate from movement. 120 125

12. The combination with a coin-counting machine, of an actuating-shaft therefor, a 130

crank having spring-pressed engagement thereon, registering means actuated by the passage of the coins through the machine, a revoluble plate carried on the registering means, one or more detents on said plate and a lever pivoted adjacent to the periphery of the plate and provided with a laterally-directed arm in position to be engaged by one of said detents and acting to swing the end of the lever inwardly into position to lock the register.

13. A coin-counting machine comprising a feed mechanism acting to carry coin to a predetermined point of delivery, registering means operated by the passage of the coins, a revoluble disk actuated from the registering

means and a plurality of detents on said disk each provided with a projecting arm and a stop-lever positioned to be adjusted by the projecting arms of one of said detents and to abut against the next succeeding detent and acting to limit the operation of the machine to a predetermined number of coins.

In testimony whereof we have hereunto subscribed our names in the presence of two 25 subscribing witnesses.
